UNITED STATES PATENT OFFICE.

ROMEO W. PRIEKORN, OF SOMONAUK, ILLINOIS.

HINGE.

1,169,566.

Specification of Letters Patent. Patented Jan. 25, 1916.

Application filed June 9, 1915. Serial No. 33,163.

To all whom it may concern:

Be it known that I, ROMEO W. PRIEKORN, a citizen of the United States, residing at Somonauk, in the county of Dekalb and State of Illinois, have invented certain new and useful Improvements in Hinges, of which the following is a specification, reference being had to the accompanying drawings.

10 My present invention relates to new and useful improvements in hinges and has particular reference to those of the type known as ball and socket hinges.

One of the principal objects of the invention is to provide a hinge of this character which is constructed with such regard to proportion, number and arrangement of parts, that it may be cheaply manufactured, will be durable and efficient in service and 20 may be readily applied to any form of farm gate or the like.

Another object of the invention is to so design the hinge that it may be efficiently applied to the gate post, adjacent to the lower end thereof to act as a support for the gate and to effectually take up the lateral and vertical thrusts which are imparted to it as a result of the swinging of the gate.

A further and more specific object of the invention is to provide a hinge which includes as its general elements of construction, a body plate having a socket wherein is received a supporting ball and a stud or plug which is removably mounted in the body plate and serves, when properly positioned therein, to prevent the displacement of the ball from the socket.

The above, and other incidental objects of a similar nature, which will be herein-40 after more specifically treated are accomplished by such means as are illustrated in the accompanying drawings, described in the following specification, and then more particularly pointed out in the claims which 45 are appended hereto and form part of this application.

With reference to the drawings, wherein there has been illustrated the preferred embodiment of this invention, as it is reduced 50 to practice, and throughout the several views of which similar reference numerals designate corresponding parts, Figure 1 is a side elevation of a gate, illustrating the same supported upon a post, by means of the hinge, 55 which constitutes the subject matter of the present invention; Fig. 2 is a detail view and

vertical section taken through the body of the hinge, showing the same applied to a gate of the tubular frame type; Fig. 3 is a detail view of a modified form of hinge, 60 showing the body member in vertical section; Fig. 4 is a section on the line 4—4 of Fig. 1; Fig. 5 is a detail view of a further modification of the hinge, showing the body member in section; Fig. 6 is a section on 65 the line 6—6 of Fig. 1; and Fig. 7 is a detail perspective view illustrating a still further modified form of hinged body member.

In taking up the detailed description of the invention, reference will first be had particularly to Fig. 1, wherein the hinge is shown as applied to a fence post and gate of the ordinary tubular frame type.

In this figure, the supporting bracket A is shown as applied to the post B to support the ball shank C, which is received within the body plate D secured to the lower terminal of one vertical frame member of the gate, indicated at E.

The attaching bracket, above generally 80 designated by the letter A, is preferably formed in the nature of a metallic casting, which includes a flat body plate 10, a horizontal plate 11, which extends at right angles thereto, and a plate 12, connects the 85 horizontal plate to the diagonal plate and serves to support the horizontal plate. The body plate of the bracket is adapted to be secured to the gate post by means of bolts or equivalent fastening devices, indicated 90 at 13.

As is best disclosed in detail in Fig. 3 of the accompanying drawings, the shank C is provided at its lower end with a threaded extension 14, and a shoulder 15. The threaded extension passes through an opening formed in the horizontal plate 11 and the shoulder 15 rests upon the upper face thereof. A nut, indicated at 16, is applied to the threaded extension to hold the shank against 130 displacement on the horizontal plate.

Upon the upper end of the shank C, is formed the ball indicated at 17. This member is adapted to be received within the socket 18, formed in the lower end of the 135 body plate D, which constitutes the other element of the hinge.

This body plate is preferably formed as a solid metallic casting in the lower end of which is formed, as above stated, the socket 110 18. Leading into this socket 18, is a substantially cylindrical opening or chamber 19,

which is defined by an annular flange 20. The socket 18, conforms of course, to the shape of the ball, but does not form a complete seat for the ball, it being necessary 5 to complete the socket for the ball by inserting the plug or stud 21. This stud or plug is removable, being seated in the chamber or opening 19 and being held against removal from the flange 20 by means of a 10 transverse securing pin, indicated at 22. Obviously, the member 21 may be removed to permit the withdrawal of the ball from the socket.

When the hinge is to be applied to an ordinary fence board gate, it is designed as in 15 Fig. 3. When the hinge is to be applied to a farm gate, however, it is shaped in the manner disclosed in detail in Fig. 5. If, on the other end, the body plate is adapted 20 for attachment to a gate of the type having a tubular frame, it is designed in the manner shown in detail in Fig. 2 so that the threaded socket may receive the threaded end of one of the vertical frame members. 25 If desired, the ball may be provided with a facial recess, as indicated at 23, for the reception of a hard lubricant, such as graphite or the like. It is, of course, necessary to hold the gate against vertical swinging 30 movement when a hinge of the type of the present invention is employed and, for this reason, I employ in connection with my hinge, the device shown in detail in Figs. 1 and 6. This device consists of a ring or 35 hoop 24, which embraces the post at the upper terminal thereof and is provided with an eye 25. A hook, indicated at 26 is provided with a ring 27, which embraces the end member of the gate frame. The bill of 40 this hook is, as shown in detail in Fig. 6 inserted in the eye. Obviously, the hook serves to support the gate against vertical swinging movement, while it is being swung, as well as when it is stationary.

45 In the modified form of the invention, shown in detail in Fig. 7 the body plate is provided with the integral, upstanding, parallel ears 28 and 29, which are spaced from each other and adapted to receive between them the frame of the gate. Aper- 50 tures, indicated at 30, may be provided for the reception of bolts or equivalent fastening devices, employed in securing the gate against displacement from the body block 55 of the hinge.

It is now to be noted that the device shown in Fig. 7 is reinforced as at 31. In this connection it is to be explained that the device of Fig. 5 is provided with rein- 60 forcements equivalent to the reinforcements 31 of Fig. 7, although they are not apparent in the figure.

In reduction to practice, it has been found that the form of this invention illus- 65 trated in the drawings, and referred to in

the above description as the preferred embodiment, is the most efficient and practical; yet realizing that the conditions concurrent with the adoption of this device will necessarily vary, it is desirable to emphasize the fact that various minor changes in the details of construction, proportion and arrangement of parts may be resorted to, when required, without sacrificing any of the advantages of this invention, as defined by the appended claims. 75

It has been found in practice, that the gate when supported by the means shown in the accompanying drawings, is prevented from swinging since the greater portion of 80 the weight of the gate is supported by the hinged element, at the base portion of the post. It has also been found that the particular form of hinge employed, makes it a relatively easy matter to swing even an unusually heavy gate. 85

What is claimed is:—

1. A hinge including a body member adapted for attachment to the article to be supported, a socket formed in the body member, a shank adapted to be secured to the structure upon which the article to be supported is mounted, a ball head formed on the terminal of the shank, said head being seated within the socket for universal 95 movement therein, and a removable plug seated in the body member for maintaining the ball head against withdrawal from the socket.

2. A hinge including a supporting bracket 100 adapted for attachment to a supporting member, a shank removably mounted in the bracket, a ball head formed in the terminal of the shank, a body member adapted for attachment to the article to be 105 supported, there being a ball receiving socket formed in the body member, said socket conforming to the head member but being adapted to form a partial seat for the ball head, and a plug removably 110 mounted in the body member and having a concave terminal engageable with the ball member for completing the seat and maintaining the ball against withdrawal from the socket. 115

3. The combination with a gate having a tubular frame, of a hinge including a body member, right-angularly disposed sleeves formed integral therewith, said sleeves being adapted to receive the terminals of a 120 pair of right-angularly disposed frame members, there being a socket formed in the body member, a shank adapted to be attached to the structure upon which the gate is supported, a ball head formed on the terminal of the shank, said head being seated in the socket, and a removable plug seated in the body member for holding the head against withdrawal therefrom. 125

4. A hinge including a body member 130

adapted for attachment to the article to be supported, a socket formed in the body member, a shank adapted to be secured over the structure to which the article to be supported is mounted, a ball head formed on the terminal of the shank, said head being seated within the socket for universal movement therein, and a removable plug disposed with its axis at approximate right

angles to the shank for maintaining the ball 10 head against withdrawal from the socket.

In testimony whereof I hereunto affix my signature in the presence of two witnesses.

ROMEO W. PRIEKORN.
